UNITED STATES PATENT OFFICE.

HARLEY L. CLARKE, OF EVANSTON, ILLINOIS.

GOLF TEE.

Application filed April 7, 1928. Serial No. 268,126.

These improvements relate to golf tees. The prime object is to provide a tee according to which a higher percentage of satisfactory shots will be had by the ordinary player than he would obtain with the usual sand tee or any tee providing merely a gravitational support for the ball.

To this end my improved tee provides means for overcoming to a notable extent the 10 effects of poor strokes resulting in "grounders," or balls leaving the tee with a low, or practically no, trajectory, the ball traveling or bouncing along close to or upon the surface of the ground. The tee is designed also 15 to provide some lateral directional effects.

In the accompanying drawings Figure 1 shows what I shall designate as the preferred form of the tee in side elevation, with a ball normally thereon and about to be struck by a 20 club of the driver type; Fig. 2 is a perspective of the tee of Fig. 1 on a somewhat enlarged scale; Fig. 3 is a further enlarged perspective of a modified form of the device; and Fig. 4 is a top plan of the device of 25 Fig. 3.

My improved tee is shown as what may be considered a molded article and of integral or unitary construction. The material employed may be metal of various well-known 30 compositions, for example celluloid, pyralin and the like. I prefer, however, to use for this purpose the composition called bakelite, the same providing a very strong and otherwise satisfactory article.

Describing Figs. 1 and 2, the ball-holding means are shown as an elongated trough-like body structure 10, important characteristics of which are the upstanding side edges 11 forming a track or runway and terminating 35 respectively in stop or rest means as 12. In my practice these substantially parallel upstanding edges 11 continue upwardly on curved lines at 13 providing surfaces against which the ball at 18 will gravitationally rest 40 when the track elements 11 are inclined upward in the normally forward direction. Between the tracks 11, as at 14 (Fig. 2), the body is preferably sufficiently hollowed or 45 otherwise given clearance in the normally downward direction to provide that the ball will normally touch and rest upon the device only on the tracks 11 and the upwardly-directed extensions 12 thereof.

The body 10 is normally supported and 50 carried by a stem, spine or spike 15 which, in Figs. 1 and 2, is shown as being conical

in shape. In the device of Figs. 1 and 2 the track elements 11 are substantially at right angles to the axis of the spike 15. At the time of use the spike as 15 will usually be 60 forced into the ground at a substantially angle to the vertical, as shown in Fig. 1, whereby the track elements 11 are directed upward at a corresponding angle. Should the driving blow be such, for example, as to 65 drive the ball forward horizontally, it would at once encounter resistance to that horizontal movement in the upwardly inclining track elements of the runway, and this resistance is communicated to the spike 15 firmly imbedded in the ground. I have demonstrated that in such case the ball is diverted upward by the track elements and that instead of the "grounder" which otherwise would have 70 ensued the shot produces a ball well clear- 75 ing the ground.

In Fig. 3 the parallel track elements 20 incline downwardly from front to rear when the spike 21 is inserted vertically into the ground, and at 22 these track elements incline upward to form a stop or final rest surface for the ball, the same as in Fig. 1. The spike 21 is shown as being pyramidal, a form better adapted to prevent twisting or 80 turning of the body on the axis of the spike 85 should the blow tend to drive the ball laterally of its intended course. On such somewhat-laterally-directed blows the ball impinges against one of the track elements, 11 or 20, encountering resistance tending to 85 overcome the effect of the misdirected blow.

According to Fig. 3 when the spike is normally inserted in the ground, with the axis of the spike perpendicular, the guiding or track elements 20 define that minimum 90 degree of elevation in the flight of the ball which it should have to result in a satisfactory shot. According to Fig. 3 the player does not need to concern himself with the angle between the direction of the track and the surface of the ground, although, should he desire a greater angle the spike as 21 could be inserted downwardly and forwardly 100 as in Fig. 1.

According to the device of Fig. 1 the 105 player inserts the spike at the particular angle which at the time and place he may prefer, so long of course as he does not get the center of gravity of the ball rearwardly beyond the retaining or stop elements as 12. 110

It is to be noted that the spike elements in both of the forms shown are substantially

thick at their respective bases and where they are imbedded in the ground. This is not only to provide notable strength, but also resistance to its movement, of one kind or another, in the ground.

It will have been observed that the arrangement of the several parts is such that the player may raise the ball as freely and as fully as he might do with some other type of tee. It is only when his stroke is too much downward or too nearly horizontal at the time of impact that the elongated upwardly-inclined runway is brought into effect.

15 I contemplate as being included in these improvements all such changes, variations and departures from what is thus specifically illustrated and described as fall within the scope of the appended claims.

20 I claim:

1. A golf tee having means for holding the ball including a pair of elongated track elements substantially parallel to each other and providing a runway for the ball, and a 25 spike element projecting normally downward from said ball-holding means and adapted to be inserted into the ground.

2. The combination of claim 1 hereof in

which there are stop means at the normally rear end of the ball-holding means for holding the ball against its rolling off of the tee when said track elements are upwardly inclined in the forward direction.

3. The combination of claim 1 hereof in which said track elements incline upwardly 35 at their normally rear end portions to provide rest surfaces for the ball.

4. The combination of claim 1 hereof in which said ball-holding means and said spike element are of integral formation and 40 said spike element is materially thick to provide firm anchorage of it when normally inserted in the ground.

5. A golf tee comprising an elongated body having upstanding sides terminating 45 in substantially parallel edges forming a runway, said edges terminating in stop means at their rear ends respectively, and a spike element extending normally downward from said body and adapted to be inserted into the ground, the device complete being of integral construction and of a strong material substantially of the character of bakelite.

CERTIFICATE OF CORRECTION.

Patent No. 1,671,813.

Granted May 29, 1928, to

HARLEY L. CLARKE.

It is hereby certified that error appears in the printed specification of the above numbered patent requiring correction as follows: Page 1, line 29, for the word "of" read "or"; same page, line 61, for the word "substantially" read "substantial"; and that the said Letters Patent should be read with these corrections therein that the same may conform to the record of the case in the Patent Office.

Signed and sealed this 10th day of July, A. D. 1928.
